Primary Examiner—Ralf Seifert*Attorney, Agent, or Firm*—Burns, Doane, Swecker & Mathis, L.P.**[57]****CLAIM**

The ornamental design for a combined key ring and lottery number selection fob, as shown and described.

DESCRIPTION

FIG. 1 is a front elevational view of a combined key ring and lottery number selection fob showing my new design, the key chain being removed for ease of illustration;

FIG. 2 is a rear elevational view of FIG. 1;

FIG. 3 is a side elevational view of FIG. 1, the opposite side view being a mirror image;

FIG. 4 is a top plan view of FIG. 1;

FIG. 5 is a bottom plan view of FIG. 1; and,

FIG. 6 is a front perspective view, shown in an alternate position with the key fob attached.
